PIEZOELECTRIC CRYSTAL APPARATUS

John M. Wolfskill, Erie, Pa., assignor to Biley Electric Company, Erie, Pa., a partnership composed of F. Dawson Biley and Charles Collman

Application April 22, 1940, Serial No. 331,050

5 Claims. (Cl. 171—327)

This invention relates to piezoelectric crystal apparatus, and more particularly to a method for mounting piezoelectric crystals.

One of the objects of the present invention is to provide a means of rigidly clamping the crystal to one of the electrodes to prevent any lateral movement of the crystal due to vibration or shock, and at the same time provide adjustable means for controlling the second electrode of the holder to permit the crystal frequency to be varied by varying the air gap between the adjustable electrode and the corresponding crystal surface.

Another object is to provide a crystal mounting which gives improved performance of the crystal over a wide temperature range.

Another object is to provide resilient clamping means for the crystal, so that the pressure is substantially evenly distributed over the clamping areas.

Another object is to provide clamping means which are independent of the second electrode of the piezoelectric crystal mounting.

Still another object is to provide clamping means for high or ultra high frequency crystals whereby the performance is greatly improved because the clamping means is remote from the active area of the crystal.

Heretofore a crystal was generally mounted between two ordinary plane faced electrodes, with spring means for holding the electrodes in contact with the crystal. It has been found that greatly improved performance may be obtained from a crystal in certain parts of the frequency spectrum by designing the electrode so as to give minimum capacity over the area of the crystal which is oscillating. I accomplish this in the present invention by cutting away a portion of one or both of the electrodes of the piezoelectric crystal and by leaving a relatively small substantially flat button shaped electrode portion preferably adjacent the center of the corresponding piezoelectric crystal face. This small button shaped electrode is adapted to concentrate the electric field substantially at the central portion of the piezoelectric crystal and at the same time decreases the detrimental electrostatic capacity of the holder present between the outer areas of the electrodes. At the same time small projections or areas of at least one of the electrodes engage the crystal adjacent to the edges thereof to clamp the crystal into the holder thus permitting the small button shaped portion of the electrode to be slightly spaced from the surface of the piezoelectric crystal to prevent abrasion.

This is important because the powder or dust produced by abrasion impairs the operation of the crystal.

Further details of this invention will be apparent to those skilled in the art to which it relates, from the following specification and drawing in which, briefly, Fig. 1 is a perspective view of an embodiment of this invention; Fig. 2 is a detail view of the bottom electrode of the crystal holder shown in Fig. 1; Fig. 3 is a cross-section of another electrode adapted for use in the holder shown in Fig. 1, and Fig. 4 is a detail view of one of the crystal element clamping strip fasteners.

Referring to the drawing in detail, reference numeral 10 designates a piezoelectric crystal element of quartz, tourmaline and the like, cut relatively thin with two major faces substantially parallel to each other or slightly convexed. The crystal element 10 is positioned on the electrode 11 of conducting material, such as, brass, aluminum, stainless steel and the like, so as to ride over the cavity or recess 12 formed in said electrode. This is illustrated more clearly in Fig. 2 where the crystal element 10 is shown in broken lines. The recess or cavity 12 does not extend entirely through the electrode but only partially so as to reduce the electrostatic capacity between it and the crystal element. In some cases it is desirable to provide a small button shaped electrode substantially to the center of the cavity 12 as shown in Fig. 3, to concentrate the electric field substantially on the center of the crystal element. This button 11a also is slightly spaced from the adjacent crystal element surface in order to eliminate abrasion between the electrode and the crystal element. If abrasion is not eliminated fine dust will be produced and this will seriously impair the operation of the crystal element if it is not periodically removed.

The corners of the crystal element 10 are resiliently clamped by the strips 13 and 15 to the more or less triangularly shaped areas 11b formed around the cavity 12. These strips 13 and 15 may be made of various materials, such as, brass, bronze, "Bakelite" and the like and, of course, are not of such weight or strength as to break or fracture the crystal element by their clamping action. Suitable threaded holes 50 are provided in the electrode 11 for receiving the screws 14 and 16 to hold the clamping strips 13 and 15, respectively, and where desired coil springs 14a as illustrated in Fig. 4 may be used on each of the screws 14 and 16 particularly where the strips 13 and 15 are made of relatively

thick material which itself does not have sufficient resilience.

A circular electrode 17 is adjustably supported by the threaded member 18 over the top of crystal element 10. This electrode also may be of brass, stainless steel or the like and is preferably flat on the surface adjacent the crystal. The member 18 is relatively tightly threaded into the bar 19 so that the air-gap between the electrode 17 and the crystal element may be adjusted and the frequency of the crystal element varied while the crystal element is oscillating, by inserting a screw driver or similar tool, preferably made of insulating material, into the groove of the threaded member 18 and rotating this member until the desired electrode air gap is obtained. The bar 19 may be of electrically conducting material to facilitate connecting the electrode 17 into an electrical circuit. However the pillars 21 are of ceramic material, such as, "Isolantite," "Alsimag," synthetic porcelain and like material preferably such as may be relatively easily lapped so that the top and bottom surfaces may be made parallel. This is important because otherwise the bar 19 would not be positioned correctly with respect to the top surface of the crystal so that the air-gap of the electrode 17 could be accurately adjusted. The pillars or bushings 21 are attached to the base 11 by suitable screws and to the bar 19 by screws 20.

The advantage of this piezoelectric crystal holder is that it gives excellent frequency stability since it improves performance of the piezoelectric crystal by tending to eliminate what is known as power or frequency jumps encountered as the temperature of the crystal and holder is varied over a substantial range. This is a rather common fault of present day piezoelectric crystal units since in most applications the temperature of the units is varied over a considerable range during which the crystal element must give satisfactory performance.

Considerable difficulty has been encountered in preventing objectionable variations in power output from the crystal controlled oscillator when piezoelectric crystal holders of types generally known in the art were employed. While the frequency variation of the piezoelectric crystal over wide temperature ranges may be kept within certain limits by employing low drift type piezoelectric crystal cuts, the problem of maintaining the power output from the piezoelectric crystal oscillator from varying beyond a certain percentage of the maximum output reached throughout the temperature range was more difficult to solve. It was found that if a low drift type of crystal element were placed between ordinary electrodes and the temperature varied from 0 to 60 degrees centigrade that the output power fluctuated over wide ranges. This was eliminated by continuing the cut and try grinding until all of the undesired couplings were practically eliminated and the crystal element became stable over the temperature range. However in the present invention this undesired power output fluctuation is practically removed by employing the piezoelectric crystal element between the special electrodes which clamp the piezoelectric crystal element securely at the corners and concentrate the electric field in the active central portion of the element. This has the tendency of discouraging any unwanted modes of oscillation which may be coupled into the length and width modes. It is in fact possible to take piezoelectric crystal elements which may have as much as a 65% change in

power output through the 0 to 60 degrees centigrade temperature range and obtain practically complete stability throughout this range by employing a holder made in accordance with this invention.

When high frequency piezoelectric crystals are employed a very small air-gap is used to reduce the damping and keep the activity of the piezoelectric crystal as high as possible. It is desirable 10 when using high frequency crystals to at times use an air-gap as low as several ten thousandths of an inch and this means that the active electrode and crystal electrode faces have to be parallel to a tolerance even less than this. Another 15 advantage of employing a slight air-gap between the working surfaces of the piezoelectric crystal element and the electrodes is that abrasion can not take place between these surfaces if the crystal should shift its position.

20 In the ultra high frequency region it is desirable to reduce the electrostatic capacity of the piezoelectric crystal holder to the very minimum in order to reduce the shunting effect of this capacity to the ultra high frequency currents produced. For this reason in addition to the other 25 reasons given the button type of electrode is employed. However it was found practically impossible to maintain a fixed position of a small button electrode relative to the crystal element 30 surface and consequently the electrode employed in the present invention consists of a small button electrode formed by cutting away the sections of the electrode between the button and the clamping corners. Cutting away or recessing 35 a portion of the electrode reduced the damping adjacent to the excited area of the crystal element and also reduced the total capacity of the holder to a minimum. It also permitted clamping the piezoelectric crystal element between surfaces 40 integral with the electrodes.

While I have described this invention in detail with respect to certain embodiments thereof it is of course understood that I do not desire to limit it to the exact details shown except in so far as 45 they may be defined by the claims.

What I claim is as follows:

1. Piezoelectric crystal apparatus, comprising: a relatively thin piezoelectric crystal having a pair of major faces substantially parallel to each other and adapted to oscillate on radio frequencies approaching the ultra high frequencies, a pair of electrodes, one for each of the aforesaid major faces of said piezoelectric crystal, one of said electrodes having portions thereof of engaging surfaces along the edge of the adjacent major face of said crystal, said last mentioned electrode having a portion of the face adjacent to the crystal cut away so that the remaining portion not cut away forms a substantially centrally disposed 50 projection extending almost to a substantially centrally disposed active portion of the crystal, a pair of strap members extending longitudinally across edge portions of said crystal element for resiliently clamping said crystal element to said last mentioned electrode, means for supporting the other of said electrodes, and means for adjusting said last electrode to or away from the corresponding crystal face.

2. Piezoelectric crystal apparatus as set forth in claim 1 further characterised in that said means for supporting the other of said electrodes consists of spacing means having the top and bottom surfaces thereof lapped substantially to parallelism.

3. Piezoelectric crystal apparatus as set forth

in claim 1 further characterised in that said means for supporting the other of said electrodes consists of a plurality of ceramic spacing pillars having the top and bottom surfaces thereof lapped substantially to parallelism.

4. Piezoelectric crystal apparatus as set forth in claim 1 further characterised in that said means for supporting the other of said electrodes consists of spacing means having the top and bottom surfaces thereof lapped substantially to parallelism, and a member attached to the top of said spacing means, said means for adjusting

said last electrode being threaded into said last mentioned member.

5. Piezoelectric crystal apparatus as set forth in claim 1 further characterised in that said means for supporting the other of said electrodes consists of a plurality of ceramic spacing pillars having the top and bottom surfaces thereof lapped substantially to parallelism, and a member attached to the tops of said spacing pillars, said means for adjusting said last electrode being threaded into said last mentioned member.

JOHN M. WOLFSKILL.
